UNITED STATES PATENT OFFICE.

ALMA P. BURROUGHS, OF SENECA FALLS, NEW YORK.

TIME-SIGNAL FOR RAILWAYS.

SPECIFICATION forming part of Letters Patent No. 230,738, dated August 3, 1880.

Application filed January 26, 1880.

To all whom it may concern:

Be it known that I, ALMA P. BURROUGHS, of Seneca Falls, in the county of Seneca and State of New York, have invented a new and Improved Time-Signal for Railways, of which the following is a specification.

Figure 1 is a rear elevation of the device, showing the actuating part thereof. Fig. 2 is a sectional side elevation on line $y y$, Fig. 1. Fig. 3 is a vertical sectional elevation on line $z z$, Fig. 1. Fig. 4 is a front elevation of the device.

Similar letters of reference indicate corresponding parts.

The object of this invention is to provide a clock device to be used on railroads to be operated by passing trains, whereby the time elapsing between the passing of one train and its next succeeding one will be correctly indicated to the engineer of the said succeeding train.

The invention consists of an attachment of combined wheels, levers, weights, &c., to an ordinary clock, whereby the clock-hands are thrown out of gear and made to return to mark twelve o'clock by the passing of trains over a certain point, when the said hands will return in gear and continue to mark the time in the usual manner until another train passes to un-gear and throw them back to twelve o'clock again.

In the drawings, A represents the clock-face with minute-hand a and hour-hand b . On the reverse are shown the minute-hand spindle B, carrying its wheel C, and the hour-hand spindle D, carrying its pinion E, and secured on the said spindles B D, respectively, are the stops $c c$. With one end made fast to the spindle B and the other end made fast to the spindle D is the cord F, in whose bight is suspended from the sheave d the weight G, so that the said weight may move readily on the said cord F.

H is a frame pivoted on the spindle f of the main driving-wheel of the clock, which driving-wheel I is shown in dotted lines in Fig. 1. Within this frame H, which is essentially a lever, the counter-wheel K and pinion L are fixed on the spindle M, and said wheel K and pinion L are made, respectively, to engage with the pinion E and wheel C when the frame H is held down by the spring g .

N represents a rail of the railroad-track, and O a lever fixed against and parallel with said rail N, and having its upper edge a little higher than the tread of said rail. In the face of this lever O, near its ends, are formed the vertical slots h , through which pass the pins i that hold it against the rail N, and these slots h permit the up-and-down movement of the said lever O as a train passes over it. Beneath the said lever O, and supporting it, are the springs k , and attached to about its center and extending at right angles toward the clock is the eccentric-lever P, whose extreme end is connected by the rod m with the end n of the frame H in such a manner that a passing train pressing upon the lever O causes, by means of the lever P and rod m , the end n of the frame H to be depressed, so as to lift and disengage the wheel and pinion K L from the opposite wheel and pinion C E, and thereby permit the weight G to operate in reversing the movement of the said wheel and pinion C E and turn the spindles B D, so that the hands $a b$ shall be carried backward to mark the hour of twelve.

In order to arrest the backward movement of the said hands $a b$ at the point of twelve on the face of the clock, the cord F and stops $c c$ are relatively arranged in such a manner that the said stops $c c$ engage with and check the unwinding of the said cord F on the instant that the said hands $a b$ return to the point twelve aforesaid. As soon as the lever O is relieved of the pressure of the passing train the said lever O is restored to its primary position by the action of the springs k , and consequently the frame H resumes its original position with the wheel and pinion K L in gear with the wheel and pinion C E, and the regular movement of the clock goes on as before, which movement winds the cord F around the spindles B D, and thereby draws up the weight G, so that by its gravity the said weight G shall again reverse the motion of the hands $a b$ when another passing train puts the herein-described mechanism in operation. Thus it will be seen that the hands of the clock or indicator will move normally only between the passing of trains, at each interruption returning to the point of twelve, so that any one on a passing train can tell at a glance by how long a time the next train ahead has preceded him. By this means the person in charge of a train can

judge how to regulate its speed relatively to the train in advance.

I do not confine myself to the precise mechanism herein shown for ungearing the hands 5 of the clock and causing them to return to a given point on the passing of a train, for it is evident that other devices may equally well effect this object; but,

Having thus described my invention, I claim 10 as new and desire to secure by Letters Patent—

The combination, with a clock mechanism, substantially as described, of the cord F, having a movable weight thereon, the spring-held lever-frame H, having end n, the rod m, the eccentric-lever P, and the slotted spring-held track-lever O, as and for the purpose specified. 15

ALMA P. BURROUGHS.
